ROTATING DISK GAME

Eugene Y. Guthmann, Philadelphia, Pa.

Application April 4, 1947, Serial No. 739,269

6 Claims. (Cl. 273—142)

1

This invention relates to game apparatus and more specifically to a chance control selective mechanism usable, either independently, or in conjunction with other apparatus in the playing of chance games.

An important object of the invention is a provision of an apparatus of this character which is in the form of a compact unit which may be readily manufactured, the elements of which are at all times maintained in assembled relation, and which may, in a single apparatus, incorporate a plurality of chance selection devices.

More specifically my invention relates to a chance controlled apparatus manipulated by the hand and having an impelling device or devices activated by hand, manipulating and impelling a chance controlled element or elements in which the utilization of ratchet mechanisms, operating springs or other fragile elements, is entirely avoided.

These and other objects I obtain by the construction shown in the accompanying drawing wherein, for the purpose of illustration, I have shown several embodiments of my invention and wherein;

Figure 1 is a plan view of a chance controlled device constructed in accordance with my invention;

Figure 2 is a semi-diagrammatic perspective view illustrating the manner in which the device is actuated;

Figure 3 is a section on line 3—3 of Figure 1;

Figure 4 is a plan view of the reverse face of the unit shown in Figure 1;

Figure 5 is a perspective view of one of the selector wheels utilized in the apparatus shown in Figures 1, 3 and 4;

Figure 6 is a combined perspective view showing the opposite faces of the other chance wheels of the structure shown in these figures;

Figure 7 is a combined perspective view showing the elements of the pivot for the chance wheels;

Figure 8 is a plan view of the obverse face of an apparatus having a slightly modified structure;

Figure 9 is a section on line 9—9 of Figure 8;

Figure 10 is a section on line 10—10 of Figure 8;

Figure 11 is a plan view of the reverse of the structure shown in Figures 8 to 10; and

Figure 12 is a perspective view of the lower selector elements employed in Figures 8 to 10.

Referring now more particularly to the drawings, the numeral 10 designates a casing element in the form of an annular wall, the upper surface of which supports a transparent closure panel 11 and the lower wall of which has an inwardly-extending flange 12 mounting or integral with a

2

second transparent closure panel 13. Mounted between the panels 11 and 13 is a pivot element 14, comprising a stud 15, having a button 16 socketed into the panel 13 as at 17, or otherwise secured thereto, this stud being mounted at its upper end in a socket formed in a button 18.

Mounted upon the stud 15, between the buttons 16 and 18, are rotatable members. Where, as in the present illustration, more than one rotatable member is employed, a separating washer 19 is arranged about stud 15 between adjacent rotatable members. In the preferred construction of the apparatus a plurality of the rotatable elements is employed, these being indicated at 20 and 21. In Figures 1 to 7 of the drawings the rotatable element 21 has, on what may be termed its inner face, or that face opposing the rotatable element 20, a series of indicia 22, these indicia, in the present instance, being shown as grouped in 20 pairs and as corresponding to the various possible combinations obtainable by manipulation of the ordinary chance die. The other of the rotatable elements indicated at 20 is provided with a window 23 through which aligned indicia of element 21 may be observed.

The peripheries of the rotatable elements 20 and 21 are provided with circumferentially spaced impelling projections 24 and 25, the projections 24 of the rotatable element 20 being differently spaced from the projections 25 of element 21. The pivot element 14, wherein before referred to, is eccentrically related to the internal wall 26 of casing 10 and arranged between the peripheries of the rotatable elements and this wall are one or more impelling elements 27, comprising spheres of a diameter such that during their passage about the path 28 between the peripheries of the rotatable elements and the wall 26, they will engage the projections 24 and 25 of both elements. The eccentricity of the pivot 14, with relation to wall 26 is such, as indicated by construction line 29, that during a portion of its travel about path 28 each impelling element 27 will contact with, or be positioned to positively contact with impelling projections 24 and 25 for only a portion of the travel so that it will intermittently impart rotation to these discs and separate therefrom to permit independent rotation of the discs. Due to the fact that the impelling projections 24 and 25 are differently circumferentially spaced, the rotatable elements 20 and 21 may, of course, partake of at least a limited relative rotation at any time with the result that the motion of the rotatable elements with relation to one another and with 55 relation to the casing is decidedly erratic.

Upon engagement it will be obvious that when

the unit is given a gyratory motion as suggested in Figure 2 of the drawings, the impelling element or elements 27 will tend to rotate about the inner wall 26. In contact therewith they will thus, through the normal eccentricity of the track, alternately come into and recede from engagement with the impelling projections 24 and 25, thus causing rotation thereof, and, since the projections 24 and 25 are differently spaced, differential rotation of members 20 and 21. This action may be considerably increased by providing that portion of the outer wall 26 forming the wider portion of the track 28 with an inward projection 30. When an impelling element during its normally free travel engages the projection 30, it is thrown violently inwardly to engage the elements 20 and 21, and their projections thus causing a further impelling action. It is to be noted that the projection 30 or its equivalent could be used to advantage also in embodiments where the rotatable elements are mounted concentrically with the wall 26 to deflect the impelling elements inwardly into operative engagement with the rotatable elements.

As above described, the rotatable elements have coaction only with one another. Obviously these rotatable elements may not only have coaction with one another, but with the casing as shown. The element 21 has upon its outer face an arrow 31 coacting with indicia 32 upon the surface of flange 12 of annular wall 10 which supports panel 13.

The structure above described is obviously capable of considerable modification as suggested in Figures 8 to 12 of the drawings. In these figures the casing comprises an outer wall 34 and end wall 35 which are integral and formed of transparent material preferably a plastic. The opposite end wall 36 is of any suitable opaque material and is provided with a transparent window or windows 37 permitting chance selected observation of indicia 38 on the adjacent face of rotatable element 39. Windows 37 may conveniently comprise molded or pressed plastic units press fitted or otherwise secured in opening 40 in end wall 36.

As at present shown element 39 has indicia on both faces thereof those upon the lower face being chance selected by alinement with a window opening 41 in a second rotatable element 42. The figures under discussion further illustrate the fact that the rotatable members are capable of varied formation. In Figures 1 to 7 both rotatable elements are in the form of disks and both serve to define the inner wall of the path of the impelling element or elements 27. Figures 8 to 12 show that it is only necessary that one of the rotatable elements define the inner wall of the track the element 42 as shown being in the form of an

arrow, which may if desired coact with indicia (not shown) on the adjacent wall 35 of the casing.

Since the constructions shown are capable of other modification I do not wish to be understood as limiting myself thereto except as hereinafter claimed.

I claim:

1. In game apparatus, a casing enclosing a generally cylindrical chamber, a propelling element movable in the chamber in a circular path concentric with the cylindrical axis of said chamber, and a rotatable index element having a radially projecting finger and mounted in the chamber for rotation about an axis offset from the said cylinder axis so that the circular path of said finger will intersect the circular path of the propelling element at one side of the casing and will lie remote to said path on the opposite side of the casing.
2. In game apparatus, a casing enclosing a generally cylindrical chamber, a rotatable index element having a radially projecting finger and mounted in the chamber for rotation about an axis offset from the axis of the cylinder defined by the chamber so that the circular path of the said finger will be in proximity to the cylindrical side wall of the chamber at one side of the latter and will be remote to said wall at the other side of the chamber, and a propelling element in the chamber confined by and movable in a circular path defined by said wall and intersecting the path first named at the one side only of the casing.
3. Game apparatus according to claim 2 where-
35 in the index element is provided with a plurality of the radial projections relatively spaced about the periphery thereof.
4. Game apparatus according to claim 2 where-
40 in the propelling element is in the form of a sphere.
5. Game apparatus according to claim 2 including a plurality of the propelling elements.
6. Game apparatus according to claim 2 including a plurality of the index elements inde-
45 pendently rotatable in different substantially parallel planes.

EUGENE Y. GUTHMANN.
